CABINET

Maude L. Butcher, Seattle, Wash.

Application September 16, 1942, Serial No. 458,512

3 Claims. (Cl. 312—186)

This invention relates to a cabinet and more particularly to portable cabinets which are internally subdivided for the segregation of contents.

In certain respects the prior art relating to cabinets of the type disclosed in this invention has been defective due to the fact that the cabinets that have been produced are either too complicated, or the parts improperly correlated and poorly designed and without other than very specific usefulness.

It is an important object of my invention, having in mind the defects of the prior art, to provide a cabinet that is simple and easy to construct and which will be extremely useful for storage of various articles and providing efficient and ready access to those contents when desired.

Another object of my invention is to provide, in a cabinet of the type described, an arrangement of shelves and drawers and compartments, all of which are readily accessible when the cabinet walls are opened.

A still further and more specific object of my invention is to provide, in a cabinet of the type described, lighting means which shines throughout the entire interior of the cabinet, making more convenient the use thereof.

The foregoing objects and others ancillary thereto I prefer to accomplish as follows:

According to a preferred embodiment of my invention, I join together certain exterior walls to define a rectangular cabinet. Within said cabinet I provide a plurality of shelves that are designed to receive and at the same time display the contents of the cabinet. On certain of the shelves I provide drawers. Cooperable between a movable wall of the cabinet and said set of drawers is provided means for causing the drawers to be pulled out of their normal closed position and disposed for ready access to their contents when said wall is moved. For the purpose of illuminating these drawers, mirrors and a light source are arranged within the cabinet so that the entire interior of the cabinet is fully and clearly illuminated when the side walls are opened for viewing or access to the cabinet.

The novel features that I consider characteristic of my invention are set forth with particularity in the appended claims. The invention itself, however, both as to its organization and method of operation, together with additional objects and advantages thereof, will best be understood from the following description of a specific embodiment when read in connection with the accompanying drawings, in which:

Figure 1 is a perspective view of my cabinet in the opened position.

Figure 2 is a fragmentary sectional perspective view of my cabinet, with the lid removed.

Figure 3 is a fragmentary sectional perspective view of my cabinet on a plane similar to that of Figure 2, but at a lower level.

Figure 4 is a vertical cross-sectional view of the cabinet, in the closed position.

Figure 5 is a cross-sectional view similar to Figure 4, but showing the cabinet in the open position, and

Figure 6 is an exploded view in perspective of certain latch means employed in connection with the drawers of the cabinet.

The cabinet itself comprises the bottom wall 10, from which rise the end walls 12 and 14. A back wall 16 extending between the upper ends of the end walls and having its lower edge terminating in spaced relation to the bottom wall 10 serves to tie the previously described end walls together in a semi-rigid manner.

The opening 18 between the lower edge of the wall 16 and the bottom wall 10 is closed by door 20, hinged at 22 to the bottom wall and secured by latch means 34. The entire opposite face of the cabinet is closed by a wall door 24 hinged at 26 to the bottom wall 10. The upper face of the cabinet is defined by the door or wall 28 hinged at 30 to the upper end of the rear wall 16. Wall 24 is latched in the closed position shown in Figure 4 to wall 28 by latch means 31 which is of the nature of a luggage hasp. A handle 32 serves to provide ready means for carrying the cabinet.

Within the interior of the cabinet is a shelf which comprises the non-transparent portion 36 and the transparent or glass portion 38, both lying in substantially the same plane. Between the shelf 36, 38 and the cover 28 of the cabinet and around the inner walls is a rack 40 as for bottles which has a plurality of loops 42 designed according to any suitable pattern for the reception and positioning of vari-shaped bottles or containers that it may be desired to dispose within the cabinet.

In the upper compartment and preferably in one of the end walls is a light socket 44 having a bulb 46 associated therewith within the cabinet. A cord 48 has a prong plug 49 for association with any convenient electrical outlet. The cord may be removed from the socket 44 by pulling the plug 50 and in that event the cord may be stowed within the cabinet.

Below the shelf 36, 38 and in spaced relation to the bottom of the cabinet is another inter-

mediate shelf 52 which is mounted at its ends on the end walls 12, 14 of the cabinet and the major portion of which is cut away at 54 as shown in Figure 3. Upon this shelf a plurality of drawers 56, 57 and 58 are mounted for sliding movement. At the rear of the drawers the side walls are extended to provide openings 59 and 60 in which the shaft 61 is mounted. The rear wall 62 of the drawers is caused to angularly overhang the shaft 61. Upon the inner face of this overhanging portion within the drawer is mounted a mirror 64.

Upon shaft 61 is a pivoted pawl 66 which has a cam face 67. A coil spring 68 is anchored at one end in the hole 69 in a drawer wall and at the other end in the hole 70 of the detent or pawl 66, and intermediately is coiled about the shaft 61. The mechanism just described is useful in cooperation with draft means devised for drawing out the drawers as the wall door 24 of the cabinet is opened. Between member 24, extending along the inner faces of the end walls 12 and 14, are the draft links 72. Their rear ends terminate adjacent a slot 74 in a depending flange of the shelf 52 and a rod 76 joins the links 72 together by passing through the slots 74. Rod 76 thus extends across the rear opening 54 in the shelf 52, as may be clearly seen in Figures 3 and 4. The downwardly extending pawl member 66 is in the path of movement of the rod 76 as it moves forwardly when the door 24 of the cabinet is opened. The drawers are pulled or extended to the position indicated in Figure 1. The forward end of slot 74 dips to such an extent that rod 76 drops, in the last short distance of its travel, out of engagement with the pawl 66. In that event, the drawers may be closed, even though the front of the cabinet is open.

The door, when subsequently closed, causes the rod 76 to move rearwardly in its guiding slot 74. When contact is made with the pawl 66 upon the cam face 67, the pawl will swing, let the rod pass and then, due to the action of the spring, snap back in place. To position the detent against movement in the opposite direction, however, a lug 78 on the inner face of the mounting wall of the drawer is contacted by the horn 73 on the pawl as can be seen in Figures 4, 5 and 6.

When the bulb 46 is ignited the upper compartment above shelf 36, 38 is fully lighted. Light also passes through the glass portion 38 of the upper shelf, impinges against the mirror 64 in the manner suggested by dashed lines in Figure 5, and is directed to flood throughout the interior of each drawer. Such light also passes through the transparent portion 38 of the shelf and the opening 56 in shelf 52 into the space below the shelf 52, lighting the space so that tools or any other manner of content of that particular portion of the cabinet may be readily visible.

The inner face of wall door 24 and the bottoms of the drawers 56, 57 and 58 may be faced with a covering of felt or other fabric 78 to prevent the marring or injury to any tools, or contents which may be laid thereon.

Although I have shown and described certain

specific embodiments of my invention, I am fully aware that many modifications thereof are possible. My invention, therefore, is not to be restricted, except insofar as is necessitated by the prior art and the spirit of the appended claims.

Having thus described my invention, I claim:

1. A cabinet, comprising: a plurality of walls joined at their edges to enclose a space, an upright wall of said group being hinged along its lower edge, a shelf above the bottom and extending from the side of the space closed by said hinged wall to a medial position within the area and providing thereby a communication opening from the space above to the space below the shelf,

10 15 a drawer slidable upon said shelf and having a lug extending downwardly through said opening, guide ways under said shelf, a bar mounted in said guide ways and movable below the shelf to engage said lug on the drawer, and link means 20 between the hinged wall and said bar to move the latter upon opening movement of the hinged wall to slide said drawer outwardly upon the shelf.

2. A cabinet, comprising: a plurality of walls joined at their edges to enclose a space, an upright wall of said group being hinged along its lower edge, a shelf above the bottom and extending from the side of the space closed by said hinged wall to a medial position within the space and providing thereby a communication opening from the space above to the space below the shelf,

25 30 a drawer slidable upon said shelf and having a lug extending downwardly through said opening, guide ways under said shelf and having down-turned forward ends, a bar mounted in said guide ways and movable below the shelf to engage said lug on the drawer, said bar disengaging said lug upon passing into the downturned ends to release the drawer for inward movement, and link means 35 40 between the hinged wall and said bar to move the latter upon opening movement of the hinged wall to slide said drawer outwardly upon the shelf.

3. A cabinet, comprising: a plurality of walls joined at their edges to enclose a space, an upright wall of said group being hinged along its lower edge, a shelf above the bottom and extending from the side of the space closed by said hinged wall to a medial position within the space and providing thereby a communication opening from the space above to the space below the shelf,

45 50 a drawer slidable upon said shelf and having a pivoted spring-pressed detent extending downwardly through said opening, guide ways under 55 60 the shelf, a bar mounted in the guide ways to engage the detent on the drawer, and link means between the hinged wall and said bar to move the latter upon opening movement of the hinged wall to slide said drawer outwardly upon the shelf, said guide ways being downturned at the outer end whereby said bar may drop out of engagement with the detent near the end of its outward travel, said detent being swingable to permit the reengagement of the bar therebehind upon rearward movement of the bar.

MAUDE L. BUTCHER.
